BUTT SEAM JOINTS FOR SHEET MATERIAL
AND THE LIKE

Franz Karl Hübner, Malmö, Sweden

Application December 28, 1955, Serial No. 555,991

Claims priority, application Sweden October 6, 1955

3 Claims. (Cl. 24—205.13)

The present invention is a development and improvement of a butt seam joint type of connection for thin sheet metal and the like which is known from German Patents 660,596 and 701,683. In a butt seam joint type of connection such as disclosed therein flat locking members are provided on pivots which are pivotally mounted on two sheet metal pieces or the like adjacent the margins to be united with each other, and each locking member has a projection which is directed radially outwardly from the pivot axis and provided with two hooks which are disposed in such a way that each hook on one of the locking members on one sheet metal piece engages around the nearest hook of one of the locking members located in staggered relation to those on the other sheet metal piece. The locking members are each disposed on a pivot secured to the metal sheet or to a special carrier strip secured thereto; that pivot is provided with a head located outside the respective locking member and having an annular groove for guiding a locking and opening slide which is displaceable along the line of connection. In order to make the locking members pivot into and out of engagement with each other respectively to engage and disengage the connection, each locking member is provided with a driver finger which is bent at an angle and which can slide in either of two curved guide grooves in the slide, thus swinging the locking member through 90° at the displacement of the slide along the line of connection.

It is an object of the invention to provide butt seam joint means for sheet metal and the like affording improved safety of the joint, an increased power transmitting capacity of the connection, and improved and safer operation in comparison with previous butt seam joints of the above kind.

Further objects and advantages of the invention will appear from the following description, reference being had to the accompanying drawings showing an embodiment chosen by way of example of the device according to the invention.

Fig. 1 is a plan view of a butt seam joint according to the invention on an enlarged scale,

Fig. 2 is an end view thereof,

Fig. 3 shows some pivoted locking members included in the butt seam joint on a still larger scale, and in positions which they can occupy in relation to each other in the joint,

Figs. 4 and 5 are views of one of the locking members and its pivot, as seen from two lateral directions perpendicular to each other.

Fig. 6 is a section on line VI—VI of Fig. 4,

Figs. 7 and 8 are a plan and a lateral view, respectively, of a detail.

Fig. 9 is a view from the underside of a slider serving to lock and unlock the joint,

Fig. 10 shows the slider as seen from the side and provided with a handle,

Fig. 11 is a cross section through the slider.

The butt seam joint shown in Figs. 1 and 2 comprises two straight strips 1 of sheet material, e.g. of steel, aluminium, brass or non-metallic material, such as a

suitable plastic, which strips are punched, in order that they may be bent in soft curves, in such a way that the remaining material runs a zigzag course. These strips are intended to be fixed, e.g. by riveting, to the marginal portions of two metal sheets or the like which are to be connected to each other, the strips being provided for that purpose with rivet holes 2. Each strip 1 is provided with a series of flat locking members 3 of metal, plastic or the like, which are each pivoted about a pivot stem 4 of the same material riveted to the respective strip. The locking members have a projection 5, as is particularly apparent in Fig. 3, which is directed radially from the pivot axis and is provided with two hooks 6 facing in opposite directions. These hooks serve to lock the locking members 3 together, each hook on one of the locking members 3 on one metal sheet 1 engaging the adjacent hook 6 on one of the two locking members 3 which are disposed in staggered relation to said first locking member on the other strip, as is shown in respect of two of the locking members in Fig. 3. Diametrically opposite the projection 5 each locking member 3 is provided with a driver finger 7 projecting perpendicularly therefrom and intended to be actuated by a slider described below in order to turn the locking member through 90° between its locking and unlocking positions. On each locking member 3 there is disposed a resilient leaf member 8 which has an aperture 8a engaging around the pivot 4 and a lateral recess 8b in the margin gripping the driver finger 7, so that the leaf member is caused to take part in the turning movement of the locking member. The pivot stem 4 is formed with an upper enlarged portion 4' above the locking member 3. This portion is of an elongated cross-sectional configuration with flattened sides and is bevelled vertically at 4", as shown in Fig. 4. The leaf member 8 is slightly arch-shaped, as seen in Figs. 4 and 8, and formed with two opposite depressed portions 8c co-operating with said enlarged portion 4' of the pivot stem 4. The member 8 will thereby be able to retain the locking member in either of the locking and unlocking positions. This function is particularly pronounced in the unlocking position, where the leaf member 8 engages the sides of the stem portion 4' in a non-tensioned condition, as is desirable in order that all locking members may then occupy the correct position for engagement by the above-mentioned slider with all driver fingers 7 after each other at the movement of the slider along the joint as will be more fully described below. As is easily realized, this makes it easy to achieve a considerably improved operational safety of the joint because obstacles to the locking, which are due to the locking members occupying different angular positions, are avoided without difficulty. The locking members may be turned into the locking position, however, by overriding the resistance offered by said leaf members. The projection 5 having hooks 6 on each locking member 3 also has two pairs of recesses, of which one 9 in each pair is located at one side of one of the hooks, whereas the other one 10 is located at the opposite side of the portion of the projection 5 which lies inside the hooks. In the locking position, in which the hooks engage each other in pairs, as has been explained above, each hook also engages inwardly above the said portion of the projection 5 on that locking member with one of whose hooks it cooperates, with the recesses 9 and 10 facing each other. Through this design it is achieved that each locking member is supported by the locking members situated on both sides thereof against forces acting perpendicularly to the plane of movement of the locking members, i.e. to the plane of the strips 1. The enlarged portion 4' of each pivot stem 4 is terminated at its top by a head 12 which is also of elongated

form with flattened sides extending in the direction of the edge to be jointed, and curved end portions, said sides and end portions being defined by edge faces 13. The pivots 4 are mounted with the said parallel sides of the heads in alignment and parallel with the joint line. The result of this arrangement is that the edge faces 13 of said parallel sides will serve as guides for a slider by which the joint is locked and unlocked, as described below, for a larger part of the length of the joint than would circular pivot heads.

The slider already mentioned for locking and unlocking the joint is shown in Figs. 9 to 11. It is made in one piece 14 of cast metal or possibly plastic and has on one of its sides two parallel guiding grooves 15 for receiving the heads 12 on the pivots 4. These guiding grooves are defined by rails 16 and 17 provided on the slider, said rails engaging under the heads 12 and cooperating with the edge faces 13, whereby they guide the movement of the slider along the two rows of pivots 4. The slider 14 has two further parallel grooves 18 formed in the bottom of the grooves 15 for receiving the driver fingers 7 on the locking members 3, the ends of the grooves 18 being broadened at 19 and 20 to form entrances for the driver fingers 7. The entrances 19 are curved softly through 90° towards the sides of the slider 14 in order that at the movement of the slider in the unlocking direction (downwardly in Fig. 1) they may impart to the driver fingers 7 such a movement that the locking members 3 are swung through 90° to the locking position. The entrances 20, however, are straight but flaring.

The slider 14 has a handle 21 which is articulated and displaceably connected therewith by means of a back flange 22 on the slider with a longitudinal slot 23 in which the guide pin of the handle is guided. This arrangement facilitates the operation of the slider, particularly where the sheet metal pieces to be jointed have curved surfaces.

Assuming that the joint is in an unlocked condition, with the strips 1 of sheet metal placed in edgewise abutting relation and the slider 14 situated at one end of the joint, at the bottom of Fig. 1, the slider is moved upwards in Fig. 1, the path of movement being positively defined by the grooves 15 engaging around the heads 12 of the pivots 4 as described above. The driver fingers 7 on the locking members 3 which are held in the position shown in the upper part of Fig. 1 by the resilient leaf members 8 will then enter the grooves 18 through the entrances 20. When reaching the entrances 19 the fingers 7 will be caused to swing through 90°, and the locking members 3 will assume the position shown in the lower part of Fig. 1 in which the hooks 6 engage each other.

What I claim and desire to secure by Letters Patent is:

1. A butt seam joint for pieces of sheet material, comprising a row of pivot members each including a stem and a head and mounted on each of said pieces by means of said stem adjacent and in fixed relation to the edge to be jointed, the stem of each pivot member including an upper enlarged portion terminated by said head, flat locking members pivotally mounted one around the stem of each of said pivot members to be capable of a turning movement through 90° between locked and unlocked positions, hook means on said locking members, said hook means on each locking member in one row interengaging in the said locked position with said hook means on two adjacent locking members in the other row located in staggered relation to the locking members in said one row, a resilient leaf member positioned around the stem of each pivot member and engaged by the associated locking member to turn positively therewith about said stem, said leaf member cooperating with said enlarged stem portion to hold said locking member in the unlocked position thereof, and sliding means supported and guided by the heads of said pivot members 75

and capable of being moved along said edges in engagement with said locking members for causing said turning movement towards the locked position thereof when moved in one direction and for causing said turning movement towards the unlocked position thereof when moved in the other direction.

2. A butt seam joint for pieces of sheet material, comprising a row of pivot members each including a stem and a head and mounted on each of said pieces by means of said stem adjacent and in fixed relation to the edge to be jointed, the stem of each pivot member including an upper enlarged portion terminated by said head, flat locking members pivotally mounted one around the stem of each of said pivot members to be capable of a turning movement through 90° between locked and unlocked positions, hook means on said locking members, said hook means on each locking member in one row interengaging in the said locked position with said hook means on two adjacent locking members in the other row located in staggered relation to the locking members in said one row, a resilient leaf member positioned around the stem of each pivot member and engaged by the associated locking member to turn positively therewith about said stem, said leaf member cooperating with said enlarged stem portion to hold said locking member in the unlocked position thereof, sliding means supported and guided by the heads of said pivot members and capable of being moved along said edges, and means on each locking member for engagement in guiding grooves provided in said sliding means for causing said turning movement towards the locked position of said member when moving said sliding means in one direction and for causing said turning movement towards the unlocked position of said member when moving said sliding means in the other direction.

3. A butt seam joint for pieces of sheet material, comprising a row of pivot members each including a stem and a head and mounted on each of said pieces by means of said stem adjacent and in fixed relation to the edge to be jointed, the stem of each pivot member including an upper enlarged portion terminated by said head, said enlarged portion and said head being of elongated cross-sectional form with flattened sides extending in the direction of said edge to be jointed, flat locking members pivotally mounted one around the stem of each of said pivot members to be capable of a turning movement through 90° between locked and unlocked positions, hook means on said locking members, said hook means on each locking member in one row interengaging in the said locked position with said hook means on two adjacent locking members in the other row located in staggered relation to the locking members in said one row, a resilient leaf member positioned around the stem of each pivot member and engaged by the associated locking member to turn positively therewith about said stem, said leaf member cooperating with the flattened sides of said enlarged stem portion to hold said locking member in the unlocked position thereof, and sliding means supported and guided by the flattened sides of the heads of said pivot members and capable of being moved along said edges in engagement with said locking members for causing said turning movement towards the locked position thereof when moved in one direction and for causing said turning movement towards the unlocked position thereof when moved in the other direction.
